CLAIM

I claim the ornamental design for a lip tint receptacle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a lip tint receptacle showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, shown in an environment of use.

In the drawings, the broken lines represent portions of the article which form no part of the claimed design. In FIG. 8, the broken lines showing a lip tint brush represent environmental subject matter and form no part of the claimed design.
